MECHANICAL PENCIL

Blanchard D. Smith, Atlanta, Ga., assignor to
 Scripto Manufacturing Company, Atlanta, Ga.,
 a corporation of Georgia

Application March 23, 1943, Serial No. 480,222

6 Claims. (Cl. 120—18)

The invention relates to pencils of the type commonly called mechanical, having provision for feeding lead outwardly or inwardly and to expel the remnant of the lead from the clutch.

It is an object of the invention to provide a pencil of this character adapted to be made very largely of plastic.

It is a further object of the invention to simplify the lead-expelling mechanism.

Further objects of the invention will appear from the following description when read in connection with the accompanying drawings showing an illustrative embodiment of the invention, and wherein:

Figure 1 is a side elevation;

Fig. 2 is a side elevation upon an enlarged scale with portions broken away to show the interior and broken out to shorten the showing;

Fig. 3 is a central vertical section with parts about to expel the lead;

Figs. 4, 5, and 6 are transverse sections upon the corresponding section lines of Figure 2 upon a still further enlarged scale;

Figs. 7, 8, and 9 are detail perspective views of the parts of the lead-feeding and expelling mechanism.

As shown the device comprises an external barrel 10 having internal screw threads as at 11, which screw threads, as indicated in Figure 5, are desirably formed as a multithreaded screw shown as consisting of four threads. Revolubly mounted in the barrel 10 there is shown a slotted tube 12, the form of the slot 13 therein being clearly shown in Figures 4 and 5. The said tube is designed to receive the lead, the end thereof being frictionally held in the end 14 of the clutch member 15, shown in perspective in Figure 8.

To propel the lead both in advance and receding movement, there is shown a nut 16 shown in perspective in Figure 9, having male thread elements 17 formed thereon to engage the internal threads 11 of the barrel 10.

The nut 16, as indicated in Figure 5, is formed complementary to the form of the slot 13 of the tube 12. Shown as formed separate from the nut 16 there is a rod member 18 seen in perspective in Figure 7, having a head 19 formed to seat within a slot 20 in the nut 16 and to therefore be moved by longitudinal motion of the nut in the slot 13 caused by relative rotation of the barrel and the tube.

The rod 18 is shown as formed with a projection 21 slidable in the clutch 15 and projecting therethrough, as indicated in Figure 6. To normally prevent relative rotation between the clutch

15 and the tube 12, the clutch is shown as formed with a projecting member 22, which also normally projects into the slot 13 of the tube 12 contacting the same at the point 23, Figure 4.

5 The projection 21 normally projects through the clutch 15 in the opening 24 thereof, which opening is shown as formed with a cam edge 25 for a purpose to be described, and the opposite edge of the slit 27 of the clutch 15 is formed with a complementary cam edge 26.

The slit 27 in the clutch 15 is shown as of sufficient width from the cam edge 26 to the point 28 to allow the projection 21 to travel therein. In the normal use of the pencil the projection

15 21 of the rod 18 is in axial alignment with the projection 22 of the clutch member and both project into the slot 13 so that the clutch and rod are prevented from rotation relative to the tube 12. In this position of the parts rotation of the

20 tube 12 causes longitudinal movement of the nut 16 carrying with it the rod 18 and the clutch 15 thereby producing feeding or retracting motion of the pencil lead indicated at 29, not shown in Figure 4.

25 When the travel of the nut brings the clutch and rod to the position shown in Figure 3, the projection 22 of the clutch comes opposite a cut-away portion 30 of the tube 12 and is therefore not prevented from relative rotation but is pre-

30 vented from further forward motion by impinge- ment of the end of the clutch tube upon the interior of the barrel 10 at 40. In this condition further outward movement of the nut 16 will cause relative movement between the rod 18 and

35 the clutch 15 causing projection 21 to impinge upon the cam edge 25 which will cause partial revolution of the clutch 15 swinging the projection 22 into the cut-away portion 30 of the tube, and continued motion of the nut 16 and the rod

40 18 will now cause travel of the projection 21 in the enlarged portion 27 of the slit in the clutch 15 causing the rod 18 to pass to the position shown in Figure 2 wherein the remnant of the lead 29 is expelled.

45 Upon retracting motion of the nut 16, the pro- jection 21 sliding in the slit 27, prevents any rotation of the clutch which would cause clutch lug 22 to leave the recess 30 of the tube, until the projection 21 contacts the face 26 whereupon

50 the clutch is given a movement of partial rota- tion, the projection 21 entering the recess 24, and the projection 22 being brought into align- ment with the slot of tube 12. This is the nor- mal working position of the parts and the clutch 55 may now be retracted to any point and a new

lead inserted into the clutch grip without disturbing the interlocked mesh of the rod projection 21 with the clutch recess 24.

It will be seen that the nut 16 and the rod 18 could equally well be made integral but by making them separate as shown, the nut 16 may readily be formed of plastic as can the tube 12 and the barrel 10.

To cause motion of rotation of the tube 12 relative to the barrel, the upper end thereof is shown as formed with a recess 31 which receives a rib 32 upon a cap member 33 which latter is crimped as at 34 into a recess 35 formed in the barrel 10. A ferrule 36 telescoping over the cap 33 is rotatably mounted on the barrel 10, having a frictional fit with the cylindrical portions of the cap 33. Therefore rotation of the ferrule 36 while the barrel 10 is held will cause rotation of the tube 12 therein.

As shown the cap 33 is formed with a rib 31 in the tube 12. It will be readily appreciated that the rib may be carried by the tube and the recess by the cap with equal facility of operation.

The ferrule 36 is shown as carrying a jacket 37 for an eraser 38.

As clearly shown in Figures 4 and 5 where the sections 4-4 and 5-5 cut through four threads, the threads in the barrel are in the form of multiple screw threads, four being chosen for purposes of illustration. This is an important feature of the invention, particularly when the barrel is constructed of plastic material.

A mechanical pencil, to be acceptable to users, must have a pitch or lead of screw thread of between $\frac{1}{8}$ and $\frac{1}{4}$ inch in order to feed the lead at an acceptable rate. The screw threads in the barrel must take the load of thrust resulting from writing pressure on the lead. In order to take this load, the nut must have sufficient bearing surface on the screw threads which can only be secured by a single deep thread or by engaging several turns of a shallower thread. In the past therefore a deep thread has been used which requires a thermo setting plastic which shrinks less than thermo plastic material but which is expensive to produce. If the single deep thread be used with thermo plastic for ejection molding the shrinkage would result in a ridge on the outside of the barrel. By use of the small multiple threads of the present invention, the barrel section becomes almost uniform in thickness and the nut may be formed to engage several of the multiple screw threads which may be shallow and yet secure the required resistance to thrust. No indication of the small multiple threads on the exterior of the barrel can be seen when the same is formed of a thermo plastic in cheaper ejection molding.

Minor changes may be made in the physical embodiment of the invention within the scope of the appended claims without departing from the spirit of the invention.

I claim:

1. A mechanical pencil comprising, in combination: an interiorly threaded barrel; a slotted tube rotatable therein; means to cause relative rotation between the tube and barrel; a lead clutch slidable in said tube having a guide projection slidable in the slot of said tube to normally prevent rotation of the clutch relative thereto; said clutch having an axial slit circumferentially displaced from said projection; a lead expelling member slidable in said clutch having a projection carrying thread sections in engagement with

the interior threads of said barrel and a projection also slidable in said slot normally in axial alignment with said clutch projection; and means whereby when sliding movement of the clutch is stopped by engagement with the end of the barrel, the member is moved into the slot of the clutch to move therein to expel the lead from the clutch.

2. A mechanical pencil comprising, in combination: an interiorly threaded barrel the bore thereof adjacent the marking end of the pencil tapering internally to an internal shoulder; a slotted tube rotatable in said bore and having a tapered end with a portion of its wall cut away adjacent said end and near but removed from axial alignment with the slot of the tube to form a recess; a clutch comprising a slotted resilient sleeve slidable in said tube, and formed with a projection to travel in the tube slot, and with a recess from its slot in axial alignment with said projection, the edge of said recess adjacent the projection tapering downwardly and outwardly; a member slidable in said clutch having a portion projecting into engagement with said internal threads and a second portion projecting through said slot into the tube slot, and normally standing in said recess; whereby when the clutch engages said shoulder continued movement of said member swings the clutch projection into said cut away recess, and said second portion into said slot, by continued movement to expel the lead from the clutch.

3. A lead clutch and expelling structure for use with a mechanical pencil having an internally threaded barrel and a slotted tube rotatable therein, said structure comprising: a sheet of resilient material bent to tubular form with meeting edges; one of said edges cut away to provide a slot, an end of said slot inclined to meet the remaining edge; the remaining edge cut away adjacent the point of such meeting to form a recess opening into said slot with one wall thereof tapering toward the slot; a lead propelling and expelling member comprising a nut portion formed to project into the threads of the barrel, a rod portion slidable in said clutch and a projection thereon receivable in said recess and movable into said slot; said rod portion projecting beyond said last named projection a distance greater than the distance between the plain end of the slot and the lead receiving end of the clutch.

4. A mechanical pencil comprising, in combination: an internally screw threaded barrel member; a longitudinally slotted tube member rotatable in said barrel member; lead controlling means comprising a nut portion having screw thread portions engaging with said internal screw threads and a clutch portion normally actuated by said nut portion; means carried by said nut portion acting to expel lead engaged by said clutch portion upon relative movement between said portions; cam means carried by one of said portions and coacting between said portions to position the same for relative movement, a portion of said clutch portion contacting a part of one of said members in the travel of said portion and thereby preventing such positioning movement by cam action; said contacted part cut away adjacent the end of the forward travel of the clutch portion to permit such positioning movement.

5. A mechanical pencil comprising, in combination; a barrel formed with multiple internal screw threads; a longitudinally slotted tube ro-

tatable in said barrel, lead controlling means slideable in said tube having a nut means projecting from said slot and formed with a plurality of screw thread portions engaging respectively a plurality of said multiple internal threads whereby to distribute writing thrust among said engaged threads.

6. A mechanical pencil comprising, in combination; a barrel formed with multiple internal

5 screw threads; a longitudinally slotted tube rotatable in said barrel, lead controlling means slideable in said tube having a nut projecting from said slot and formed with a plurality of screw thread portions engaging respectively a plurality of said multiple internal threads, a clutch portion confined within said tube and coupled with said nut for normally gripping the lead.
